UNITED STATES PATENT OFFICE.

HORATIO G. GILLMOR, OF WASHINGTON, DISTRICT OF COLUMBIA

RAIL ANCHOR.

Application filed June 25, 1924. Serial No. 722,317.

To all whom it may concern:

Be it known that I, HORATIO G. GILLMOR, a citizen of the United States, residing at Washington, in the District of Columbia, have invented certain new and useful Improvements in Rail Anchors, of which the following is a specification.

My invention relates to devices for resisting the longitudinal creeping movement 10 of railroad rails. Such devices are commonly known as rail anchors, anticreepers, creepchecks, or rail stays.

One of the objects of my invention is to produce a device of this character which 15 may be formed from a rolled steel bar, which may be easily and cheaply manufactured.

Another object of the invention is to produce a device of this character which will 20 be simple in construction, easily applied using only the tools ordinarily carried by track workers and readily removed when removal is desired, using only the same tools; and which will take a firm and reliable grip upon the rail and retain its position thereon without being loosened or its efficiency impaired by contraction or expansion of the rail, freezing of the ballast or other effects of weather conditions, vibrations or any of the other causes tending to loosen the grip or impair the efficiency of 25 devices of this character.

A further object is to provide a device 30 which may be repeatedly removed, when desired, from the rail and re-applied to the same or another rail repeatedly and be tight and efficient in preventing creeping after such repeated removal and re-application.

40 In order that my invention may be fully understood, I have described, as an example, one embodiment thereof in the following specification, and shown the same in the accompanying drawings, in which:

45 Figure 1 is an elevation, with the rail in section, and Figure 2 a side elevation, with the cross tie in section, showing the device in position. Figures 3 and 4 are elevations, with the rail in section, illustrating the 50 method of applying the device to the rail. Figure 5 is an elevation with the rail in section, illustrating the method of removing the device from the rail.

55 Like characters of reference refer to like parts in the several figures.

The form of rail anchor shown in the

drawings consists of a steel bar of rectangular cross section, the body portion A arranged to extend transversely beneath and some distance below and out of contact with the base flange B of the rail. The two ends of the bar are bent to form a short curved arm C, the upper inner corner D of which is arranged to engage and press upon the vertical edge of one base flange B; and a relatively long, reversely curved arm E, comprising a straight portion F arranged to engage the top of the base flange B and a portion extending upwardly from the portion F, having a bend at G and terminating in an end surface H which is approximately at right angles to the unbent bar so that it may be the sheared end of the bar and require no forming to adapt it to engage the underside of the head I of the rail at one side of the rail. The terminal arm E is of the general form which the fish bar, employed to form the joint where two rails join, would have and is arranged to be wedged into the fishing space 60 between the head and base of the rail at some point in the length of the rail adjacent a tie K with the face of the body portion A in contact with the tie K and the upper corner D of the short arm C pressing firmly against the vertical edge of the base flange B at the side of the rail opposite to that gripped by the longer arm E.

The proportions and shape of the body 65 A and the two arms C and E are such that the inner corner D of the short arm C will when the body A is in the unstressed condition come within the plane of the vertical edge of the rail base B, when the longer arm E is wedged into the fishing space between the head I and base flange B of the rail. This will be readily understood from Figure 1, in which the dotted lines indicate the form which the body portion A and the arm C have normally in the unstressed condition. To get the device into its operative position on the rail the short arm C has to be deformed or sprung to the form shown in the full lines in Figure 1. In seeking to resume the form from which it was sprung the inner corner D, in contact with the vertical edge of the rail base B, firmly grips the rail base and through the body portion A, holds the long arm E wedged into the fishing space at the other side of the rail.

In applying the device to the rail, the

longer arm E is brought in an inclined position, into the fishing space between the head I and base of the rail, with the body portion underneath the base flange B. The curved portion L, between the body A and the arm E, is arranged to provide internal clearance sufficient to permit the short arm C to be brought up past the edge of the base flange B at the side of the rail away from the arm E. The position of the device, when the arm C is about to clear the edge of the base flange B is illustrated in Figure 3. When this position is reached, the arm C is brought up by the edge of the rail base B and the device is then turned to the vertical position as shown in Figure 4. The curved portion M is arranged to provide clearance sufficient to permit the end H of the arm E to be brought cut clear of the head I of the rail and thus permit the device to be swung to the vertical position. The device is then moved longitudinally on the rail until one face of the body portion A engages the tie K, after which it is moved transversely and angularly on the rail until the surface H of the arm E begins to engage the under side of the head I of the rail. The arm C will then engage the upper corner of the rail base flange B and the device will be in the position in relation to the rail shown in Figure 4. Force will now be required to effect the deformation or springing of the device necessary to bring it to the final gripping position shown in Figures 1 and 2. This may be done by striking the arm E in the direction of the arrow N toward the rail, and the end of the arm C in the direction of the arrow O downwardly. Several blows may be necessary but the grip of the device upon the rail in the intermediate positions, after the surface H once begins to engage with the under side of the rail head L, is sufficient to hold the device in place and permit it to be driven to the final operative position. When the inner corner D of the arm C has thus been sprung over the upper corner of the rail base and into contact with the vertical edge of the base flange B, the arm E should be well wedged into the fishing space by several heavy blows at about the bend G in this arm E, in the direction of the arrow N.

The direction in which the rail tends to creep is indicated by the arrow in Figure 2. It will readily be understood that, with the arm E firmly wedged in between the head I and base flange B of the rail and there held by the gripping action of the arm C upon the opposite vertical edge of the base flange B, the contact of the body portion A with the tie K will prevent movement of the rail forward in the direction of the arrow in Figure 2. The grip of the device on the rail will ordinarily be sufficient

to effectually resist the tendency to creep. Should, however, this initial grip be not sufficient and the rail tend to move forward, such forward movement of the rail will carry the upper end of the arm E forward with the rail, while the lower end, held by the contact of the body portion A with the tie K, will not move forward. The arm E will thus be brought to an inclined position, as shown by the dotted lines in Figure 2, and the grip of the device automatically increased by the tilting of the arm E, wedged in between the head I and base flange B of the rail, until sufficient to withstand the forces tending to produce creeping.

It will readily be understood that the arm E, when wedged into the fishing space as described above, is subject chiefly to compression stresses and that the tilting of this arm increases such compression stresses. The functions of the body portion A and arm C is to retain the arm E in tightly wedged position and to engage the tie K in opposition to the tendency to creep; and while the arm C does have some gripping action upon the base flange B such action is due to the tendency of the piece to resume the original form which it had before application to the rail. There is nothing in the action of the device after application to the rail tending to increase the stress upon the arm C and body portion A to cause them to yield and permanently deform. It is well known that material subject to compression stresses can withstand greater stresses and is subject to less deformation under such stresses than material subject to tension, torsion or bending. The body A and arm C have sufficient resilience to permit the necessary change in shape to permit the device to be applied to the rail without permanently deforming them and the arm E, which exerts the main gripping action upon the rail, is subject to compression chiefly, so that the device is fully capable of withstanding all the stresses to which it may be subjected in service without any permanent deformation which would loosen the grip of the device upon the rail or permit it to become inefficient or drop off the rail.

The bend G in the arm E of the device serves the double purpose of bringing the end surface H of the arm E to the angle corresponding with the angle of the under side of the head I of the rail, so that the sheared end of the bar may form the surface H; and of providing a suitable surface to receive the blows directed to the proper seating and wedging of the arm E into the fishing space.

It will readily be understood that since the end surface H of the arm E may be the sheared end of the bar and some variation,

within permissible limits, may be made in the length of the arm C, the device may be fashioned from a rolled bar by bending alone without forging. Bars of the proper 5 length may, in one operation, be bent to the form required for the completed device. The manufacture is thus made simple and inexpensive.

Should it be desired to remove the device 10 from the rail, the arm C is driven downwardly by blows in the direction of the arrow P upon the end of the arm C as shown in Figure 5. The dotted lines in Figure 5 show the position of the device when in operative position on the rail. The resiliency 15 of the arm C and body portion A permits the arm C to be driven down, with the corner D riding upon the vertical edge of the rail base until the position shown in Figure 5 is reached. The end of the arm C will then 20 clear the base flange B and the device drop from the rail. The resiliency of the material of which the device is constructed is sufficient to cause the device to resume the 25 form which it originally had in the unstressed condition.

While I have described in the foregoing specification one form of rail anchor embodying my invention, I wish it understood 30 that changes may be made in the details thereof without departing from the scope of the invention as defined by the appended claims.

I claim:

35 1. A device for preventing the longitudinal creeping of rails comprising a bar extending substantially transversely beneath the rail base adapted to engage a tie in opposition to the tendency of the rail to creep, having one sheared end surface substantially at right angles to the bar adapted to engage the under side of the rail head at one side of the rail, and the corner of the other end thereof adapted to engage the rail base flange at its other side, and an intermediate portion extending over and adapted to engage the top of the base flange below the rail head engaging end of said bar, said bar and the ends and intermediate 40 portion thereof being so formed in relation to each other that said bar exerts an upward pressure upon the head and a downward pressure upon the base flange at one side of the rail and a lateral pressure upon its base flange at the other side.

2. An anticreeper comprising a bar bent to form a body, adapted to engage a tie in opposition to the tendency of the rail to creep and end arms in the same plane therewith, one end arm being bowed and adapted to engage its upper end with the under side of the rail head and provided with a portion adapted to engage the upper surface of the base flange at one side of the rail and the other end arm adapted to engage its in-

ner corner with the rail base flange at the other side of the rail, the arrangement being such that with one arm entered in the space between the head and base at one side the other arm is free to rise and be brought into engagement with the rail base flange at the other side and that when said arm is brought into full operative engagement with the rail base at its inner corner and said arm first named is forced in between the head and base flange of the rail, said bar is distorted.

3. A rail anchor of one piece of resilient material formed to provide a long bowed arm adapted to be forced in between the head and base flange at one side of the rail and a short arm adapted to engage the edge of its rail base at the other side, the two arms being connected by a body portion adapted to engage a tie, the form of the two arms and connecting body portion being such as to permit the device to be applied to a rail with the short arm engaging the base flange below the end of said arm and with the long arm engaging the upper corner of the base flange and the lower corner of the rail head and then, by distortion of the device, to bring the inner corner of the short arm into engagement with the edge of the rail base at one side of the rail and the long arm into full engagement with the rail head and base flange at the other side of the rail, whereby the long arm will be put under compression and the body portion under 50 spring tension.

4. A device for preventing the creeping of rails comprising a bar bent to form a long arm adapted to be forced in between the head and base flange of a rail at one side, a short inturned arm adapted to be forced into engagement at its inner corner with the edge of the base flange of the rail at the other side, and an intermediate body portion, all so formed and related that transverse angular forced movement of said bar upon a rail will cause the device to grip the head and base flange at one side of the rail and the edge of the base flange at its other side, and that longitudinal movement of the rail when said intermediate body portion is in contact with a tie will automatically increase the grip of the device upon the rail.

5. A device for preventing the creeping of rails comprising a bar adapted to engage one end thereof with the vertical edge of the base flange at one side of the rail and to engage the other end and an intermediate portion with the rail head and upper surface of the base flange at its other side, and provided with a transverse portion beneath and out of contact with the rail base adapted to engage a tie, all so arranged and related that, with said transverse portion in contact with a tie, longitudinal movement of the rail toward the tie

will automatically increase the grip of the device upon the rail.

6. A rail anchor comprising two end arms of unequal length, the longer bowed and engaging the head and the base flange at one side of the rail and the shorter engaging at its inner corner only the base flange at the other side of the rail, and a body adapted to engage a tie in opposition to the 10 tendency of the rail to creep.

7. A one piece anticreeper formed of a bar of resilient material having a relatively long arm at one end with an end surface substantially at right angles to said bar, a relatively short arm at the other end and an intermediate tie engaging portion, all so formed and related that the long arm may be forced in between the head and base of the rail at one side and the end of 20 the short arm brought into gripping engagement with the vertical edge of the rail base at its other side.

8. A rail anchor comprising a body member having terminal rail gripping arms, 25 one of which is shorter than the other, said arms being so disposed with relation to the body that their grip upon the rail is tightened by simultaneous angular movement on the rail in a plane transverse thereto, and 30 a full operative engagement is secured by continued angular movement of one arm after the other has attained its final gripping position.

9. A rail anchor comprising a body member having terminal rail gripping arms of unequal length, the longer engaging the head and base of the rail at one side and the shorter the base of the rail at the other side, said arms being so related to the body 40 that full operative engagement with the rail is secured by successive angular movements of the anchor in a plane transverse to the rail until the body is stressed.

10. An anticreeper having a body adapted 45 to lie beneath the rail, to engage a crosstie, but out of contact with the bottom of the rail base flange when in operative position, a short arm rising from one end of said body for gripping the edge of said flange 50 at one side of the rail base, and a long arm rising from the other end of said body and bent to be received between the rail head and base at the other side of the rail, said anticreeper being adapted to be locked in 55 operative position on the rail by pressure thereon from said two arms due to a progressive deformation of the anticreeper, while being applied to the rail, from its unstressed state when off the rail.

60 11. A one piece anticreeper for rails comprising a bar of resilient material bent to form an angular arm at one end having an upper portion, adapted to occupy the fishing space at one side of the rail and 65 engage the under face of the rail head with

its free end, and an out-turned lower portion adapted to engage the upper face of the rail base flange at that side, and bent to form a relatively short arm at its other end, disposed substantially opposite said 70 out-turned portion of the angular arm, adapted to engage the edge of the rail base at the opposite side, said short arm having its position relative to the angular arm shifted, both vertically and horizontally, 75 when the anticreeper is in full operative engagement with the rail.

12. An anticreeper having a body adapted to extend across the rail and engage a cross-tie, said body having terminal arms to engage with the rail at either side of its web, one arm being relatively short and turning slightly inward toward the other arm, and the other arm being relatively long with its lower portion turned inward over the rail base flange and having an upper portion adapted to seat within the fishing space of the rail, said anticreeper being locked in position on the rail by pressure thereon from said two arms built up by a transverse angular movement of the anticreeper and its consequent deformation by springing the two arms apart due to the wedging action of the rail between them.

13. A device for preventing creeping of rails comprising a body extending transversely under the rail base adapted to engage a tie but not the bottom of the rail base, an arm at one end of said body adapted to extend over one side of the rail base flange and upward to engage the sheared end of said bar with the under side of the rail head, an arm at the other end of said body adapted to extend to the edge of the base flange at the other side, said arms and said body being so formed in relation to each other that said arm first named exerts an upward pressure against the rail head and a downward pressure against the base flange at one side, and said other arm exerts pressure laterally against the base flange at the other side when the device is applied to the rail.

14. A rail anchor including a transverse body member adapted to engage a tie but not the bottom rail base and end arms formed on the body member for securing the rail anchor to the rail, said end arms being so disposed with relation to the body member that their grip upon the head and base of the rail is tightened by movement together in a plane transverse to the rail.

15. In an anticreeper a body, adapted to bear against a crosstie, disposed so as to be out of contact with the bottom of the rail base, and end portions disposed so as to rigidly engage the under side of the head and the upper side of the base at one side of the rail and the edge of the rail base at the other side of the rail, when said body is

- forcibly moved angularly transversely of the rail, and thereby lock said anticreeper in position on the rail.
16. A rail anchor comprising a body member adapted to engage a crosstie below and to be held out of contact with the bottom of the rail base, and end portions formed on the body member for securing said anticreeper to the rail, said body member being adapted to be forcibly moved on the rail after being placed thereon whereby one end portion is wedged in between the under side of the head and the upper side of the base at one side of the rail and the other end portion firmly pressed against the edge of the rail base at the other side of the rail.
17. An anticreeper formed of a single bar of metal bent to form a body portion adapted to engage a crosstie but not the bottom of the rail base, an arm at one end adapted to engage the edge of the rail base at one side of the rail, and a portion at the other end adapted to be forced in between the under side of the head and the upper side of the base at the other side of the rail.
18. A one piece anticreeper comprising a body having a portion adapted to be forced in between the head and base of the rail at one side of the rail, a portion adapted to engage the edge of the base at the other side of the rail, and a portion adapted to engage a crosstie beneath the rail, said portions being so arranged and disposed as to permit said anticreeper to be first placed upon the rail with said crosstie engaging portion below and said base edge engaging portion above the rail base and then forced into position by forcing said edge engaging portion downwardly and said portion first named in between the head and base of the rail.
19. A rail anchor comprising a bar bent to form a body portion adapted to engage a crosstie below but to be out of contact with the bottom of the rail base, an end portion adapted to be driven in between the bottom of the head and the top of the rail base at one side of the rail, and an end portion adapted to engage the vertical edge of the rail base at the other side of the rail.
20. An anticreeper comprising a bar having one end bent to form a portion adapted to be forced in between the under surface of the head and the upper surface of the base at one side of the rail and the other end bent to form an arm adapted to rigidly engage the vertical edge of the rail base at the other side of the rail, said arm being so disposed with relation to the other portion that said anticreeper may first be placed upon the rail with the intermediate portion of said bar in contact with a crosstie below and with said arm and other end portion above the base of the rail, and then forced into position by driving said arm down-wardly and said other end portion in between the head and base of the rail.
21. A one piece anticreeper comprising two terminal arms of unequal length, the longer engaging the head and base of the rail at one side and the shorter the base of the rail at the other side, and a body held out of contact with the rail when said anticreeper is in operative position on the rail.
22. A rail anchor comprising a body and end arms extending upwardly substantially in the plane of the body, being so arranged that clearance is provided for applying the device with the body extending across beneath the rail and out of contact therewith and with the arms in preliminary engagement with the rail head and base at one side and with the base at the other side of the rail, the parts being so positioned and proportioned that upon angular movement of the device upon the rail into its operative engaging position the device is forced into strong gripping engagement with the rail.
23. The combination with a crosstie and a railroad rail having a head and base flange, of an anticreeper provided with a part engaged with the rail head and the top of the base flange, and a second part, extending transversely of the rail from the part first named, engaged with the crosstie and the edge but not the bottom of the base flange.
24. The combination with a crosstie and a railroad rail having a head and base flange, of an anticreeper provided with a part engaged with the bottom of the head and the top of the base flange, a part engaged with the crosstie to prevent forward movement, and a part engaged with the vertical edge only of the base flange to prevent lateral displacement.
25. A rail anchor, comprising a transverse bar constructed to engage a crosstie but not the rail bottom and provided with a terminal arm at one end constructed to engage the rail base edge, and with a portion at the other end thereof constructed to be driven transversely of the rail toward and under the rail head to effect a gripping action and lock said anchor in position.
26. An anticreeper for rails comprising a body and two terminal arms so arranged that lateral clearance is provided for applying the device to the rail with the body out of contact therewith and with the arms in preliminary engagement with the rail base and head at one side and with the base at the other side of the rail, and so arranged that the device is movable transversely of the rail from its position of preliminary engagement into its operative engaging position and is thereby forced into strong gripping engagement with the head and base of the rail.
27. A one piece anticreeper formed of a

bar of resilient metal bent to form a long arm at one end and a relatively short arm at the other end and an intermediate portion, all so formed and related that the long arm may enter the space between the head and base of the rail at one side and the short arm be brought into gripping engagement with the base at the other side of the rail with the intermediate portion out of contact with the rail.

28. An anticreeper comprising a body, and end arms formed integrally with said body and in the same plane therewith adapted to have direct engagement with the head

and base at one side and with the base at 15 the other side of a rail, the arrangement being such that with one arm entered in the space between the head and base at one side the other arm is free to ride on the rail base at the other side to a position of engagement with the vertical edge thereof, and that when said arm is brought into its full operative engagement with the rail base on its side and said arm first named is forced in between the head and base of the rail on the 26 other side, said body is stressed.

H. G. GILLMOR.
